UNITED STATES PATENT OFFICE.

RICHARD E. LUNSFORD, OF DORSEY, GEORGIA.

PLOW.

No. 814,551.

Specification of Letters Patent.

Patented March 6, 1906.

Application filed September 20, 1905. Serial No. 279,318.

To all whom it may concern:

Be it known that I, RICHARD E. LUNSFORD, a citizen of the United States, residing at Dorsey, in the county of Morgan and State of Georgia, have invented certain new and useful Improvements in Plows; and I do hereby declare the following to be a full, clear, and exact description of the invention, such as will enable others skilled in the art to which it appertains to make and use the same.

My invention relates to plows; and its object is to provide a durable device of this character formed of but few parts which will not become easily disconnected and having a scraper of novel form, both the scraper and the plow being adjustably connected to the stock.

The invention consists of a stock formed of metal bent upon itself and curved from end to end, the clevis being adapted to be connected to the ends of said metal strip, while the intermediate or looped portion thereof constitutes the foot. A scraper of peculiar form is adjustably mounted upon the rear portion of the foot, while the plowshare is similarly connected to the opposite portion of said foot, and both of these adjustable parts are held in place by means of a single fastening device.

The invention also consists of certain other novel features of construction and combination of parts which will be hereinafter more fully described, and pointed out in the claims.

In the accompanying drawings I have shown the preferred form of my invention:

In said drawings, Figure 1 is a perspective view of my improved plow. Fig. 2 is a vertical section therethrough; and Fig. 3 is a detail view of the scraper detached, the central portion of said scraper being broken away at its upper edge and shown in section.

Referring to the figures by numerals of reference, 1 is the stock of the plow, the same being formed of a strip of metal curved from end to end and bent upon itself at the center to form a U-shaped foot 2. The ends of this strip are enlarged at 3 and provided with openings 4, in which suitable draft devices may be fastened. The edges of the strip are notched in the foot portion thereof, as shown at 5, and the notches within the front portion of the foot are adapted to receive a flange 6, formed at the upper edge of a plowshare 7, having an elongated slot 8 therein. This slot is adapted to receive a clamping-bolt 9, which projects through the U-shaped foot 2

and through an opening 10 formed adjacent the center of a scraper 11. This scraper is in a single piece of metal and consists of similar wings extending backward at acute angles from the center and having a tongue 12 projecting forward from the central portion of the scraper and into the foot 2. A flange 13 is formed adjacent the upper edge of the central portion of the scraper and is adapted to engage any of the notches 5 in the rear of the foot. A thumb-nut 14 is mounted on the bolt 9, and by tightening it the plowshare and the scraper can be clamped upon opposite faces of the stock with their flanges 6 and 13 within the notches adjacent thereto. By loosening the bolt 9 either the plowshare 7 or the scraper 11 can be adjusted vertically, so as to assume any desired relation to each other, and by tightening said bolt the two parts can be securely bound immovably upon the foot 2.

It will be noticed that the plow such as herein described embodies in its construction but four parts, to wit: the stock and foot, the plowshare, the scraper, and the securing means for the share and scraper. There are therefore very few parts to become displaced or get out of order, and the device will be found to be very durable as well as efficient and inexpensive.

Having thus fully described my invention, what I claim as new, and desire to secure by Letters Patent, is—

1. The combination with a slotted plow-share having a flange at one end and an angular scraper having a flange; of a stock formed of a curved strip of metal folded upon itself at the center and having its ends enlarged and apertured, the edges of said strip being notched adjacent the fold and adapted to be engaged by the flanges, and securing means extending through the slot in the plow-share and through the scraper.

2. The combination with a stock comprising a curved metal strip folded upon itself and having notches in its edges; of a slotted plowshare upon one edge of the stock and adjacent the fold, a scraper upon the other edge of the stock and adjacent the fold, flanges extending from the share and scraper and adapted to be seated in the notches, a tongue extending from the scraper and into the stock, and means extending through the slot in the share and into engagement with the scraper for clamping the share and scraper upon opposite edges of the stock.

3. A stock for plows formed of a curved strip of metal folded upon itself at the center and having its edges notched adjacent the fold, the ends of said strip being spaced apart 5 a greater distance than the notched portion thereof and enlarged and apertured for the reception of draft means between said ends.
4. The combination with a slotted plow-share, having a flange at one end, an angular 10 scraper having a centrally-disposed flange at one edge and a tongue at the opposite edge; of a stock formed of a curved strip of metal folded upon itself at the center and having its 15 ends enlarged and apertured, the edges of said strip being notched adjacent the fold,

and adapted to be engaged by the flanges; the tongue on the scraper extending into the fold, the ends on said strip being spaced apart a greater distance than the notched portions thereof, and securing means extending through the slot in the plowshare and through the scraper. 20

In testimony whereof I have signed my name to this specification in the presence of two subscribing witnesses.

RICHARD E. LUNSFORD.
